UNITED STATES PATENT OFFICE.

WILLIAM F. HUNTER, OF ARCATA, CALIFORNIA.

DIPPER-DREDGE.

1,177,108.

Specification of Letters Patent. Patented Mar. 28, 1916.

Application filed May 31, 1912. Serial No. 700,787.

To all whom it may concern:

Be it known that I, WILLIAM F. HUNTER, a citizen of the United States, residing at Arcata, in the county of Humboldt and State of California, have invented new and useful Improvements in Dipper-Dredges, of which the following is a specification.

This invention relates to new and useful improvements in dipper dredges, and more particularly to a dredge which is adapted to remove gold bearing gravel, or similar valuable deposits from river beds.

The object of this invention is to provide a dredge of this character whereby the gravel, or other valuable deposits, may be gathered from the bed of a river below the deck of the dredge and lifted to a hopper above the deck of the dredge without losing a particle that may have found its way into the dipper.

A further object of this invention is to provide means for operating the dipper or scoop whereby the same may be operated by one man at a predetermined point, and means whereby the operator may move, hold or force this scoop in any position below the point of dumping and the depth which he wishes to remove the material.

This dipper dredge when used for removing gold bearing gravel and other such valuable deposits found in the bed of a river is to be operated in conjunction with my hydraulic dredge set forth in Letters Patent of the United States #974,150, dated November 1, 1910.

With these and other objects in view this invention consists of the novel construction, combination, formation and arrangement of parts as will hereinafter more clearly appear, claimed and particularly pointed out in the appended drawings, in which:

Figure 1 is a side elevation of a dredge having my improved mechanism applied thereto; a portion of the cabin and roof of the dredge being broken away to more clearly illustrate the different parts thereof. Fig. 2 is a plan view of the same. Fig. 3 is a front elevation of the same. Fig. 4 is a side elevation of my improved scoop showing a part of the dipper in elevation. Fig. 5 is a plan view of the dipper arm illustrating more clearly the off-set portion formed therein. Fig. 6 is a front elevation of the scoop illustrating more clearly the operation of the dumping hook. Fig. 7 is a vertical longitudinal section taken

through a portion of the adjustable operating handle. Fig. 8 is a plan view of the operating hook. Fig. 9 is a plan view of the swinging pulley which is adapted to support the cable holding the scoop. Fig. 10 is a front elevation of the swinging pulley as shown in Fig. 9. Fig. 11 is a detail side elevation of the grooved pulleys for receiving the adjustable operating handle and also illustrating the slideable pulley in one position in dotted lines. Fig. 12 is a section taken on line 12—12 in Fig. 1 in the direction of the arrows shown. Fig. 13 is an enlarged detail view to better illustrate the means for supporting and holding the dipper in the dumping position.

In describing my invention in detail, wherein similar parts are illustrated by similar characters throughout the several views, I will first describe the portions of my invention which are shown in Figs. 1, 2 and 3 of the drawings.

The letter A indicates an ordinary floating dredge having mounted thereon my improved operating mechanism which is to be completely covered by a roof in the usual and well known manner, the greater portion of the roof being broken away to more clearly illustrate my invention, but for the sake of illustration a portion B is shown upon the stern of the dredge.

Mounted in the bow end of the dredge are supporting members preferably in the shape of a well known wood horse and increasing in size, these supports being illustrated by the numerals 10, 11 and 12, respectively. A pair of diagonally extending supports 13 are mounted within the first mentioned supports one end of each of which extends beyond the support 12 and is connected thereto, while the opposite or lower end is fixed in any suitable or well known manner to the bottom of the dredge. Formed in the forward end of the bow portion of the dredge and approximately the center thereof is an elongated opening 14 in which operates the scoop or dipper 15. This scoop 15 has extending therefrom an adjustable arm 16 which is slidably and turnably supported in the groove of a roller 17 mounted between the diagonal members 13 and supported by brace members 18 which are connected to the diagonal members, as more clearly shown in Fig. 1 of the drawings.

On the dredge is a hoist 19 having mount-

ed a plurality of drums over which pass operating cables which will be hereinafter described. A cable 20 extends from one of these drums and over a swinging pulley 21 mounted in one extremity of the diagonally extending members 13 and is connected to the scoop 15. Another cable 22 is mounted on one of these drums and extends over a pulley device mounted on support 13 and around the grooved pulley 17 and is fixed to one extremity as at 24 of the arm 16. A third cable 25 is mounted on one of the drums and extends over the pulley of a pulley device 27 fastened on support 13, then over a slidably mounted pulley 28 mounted within the support 18, as will be hereinafter more fully described, and connected to the operating arm as at 29. The lowermost position of the slidable pulley 28 is shown in dotted lines in Fig. 1. It will be seen from the arrangement of the foregoing cables that the cable 20 will form means for drawing the scoop through the bed rock or gravel C found in the bed of a river. This cable may be used for getting different hauls on the dipper, that is when the cable is in the position illustrated by 20', the scoop when getting a load will only take the gravel or rock from the top of the bed rock, but when it is extended over the pulley 30 mounted in the bow end of the dredge, as illustrated at 20'', the scoop will go deeper into the bed rock and thereby obtain a larger load. The cable 22 which is secured to one end of the arm 16 as at 24 is adapted to draw the scoop down and force it into the bottom of the bed rock and the cable 25 is used for lifting the dipper in a vertical position from the bottom of the river when the scoop is used in obtaining the gravel from very deep channels. It will be seen from the cables 22 and 25 that this dipper may be held in a rigid position, or the same raised and lowered at the will of the operator and also that the cable 20 may be used to gather the desired load, as before described.

A plurality of drums are mounted within a suitable winch in the usual and well known manner as illustrated by the numeral 31 in Fig. 2 of the drawings. Extending from these drums are three cables 32, 33 and 34, respectively, which are extended over fixed pulleys mounted on the bow of the dredge and these cables are anchored or fixed in some well known way in the river, or on the banks thereof, thereby providing suitable means for maintaining stationary or moving the dredge within the channel of the river. The cables 35 and 36 are wrapped or wound around drums of the winch 31 and extend to a fixture on the shore or a point opposite the dredge so that the cables may be attached to a scow or other boat and the winch thereupon operated to draw the boat to or from the dredge. Another cable 37 is

mounted on one of the drums mounted in the winch 31 and is connected to the suction pipe whereby the different sections of the pipe which are detachable can be raised out of the water when occasion requires. Another cable 39 is mounted on one of these drums mounted in the winch 31 and is run over fixed pulleys mounted in the stern of the scow and has formed on one end thereof a hook 39' by which the diver may move the larger rocks back on the cleaned bedrock, as more clearly illustrated in Fig. 1 of the drawings. Mounted on suitable rafters, or supporting members 40 is a slanting hopper 41 and extending therefrom is a 80 tramway 42 mounted on the scow and having mounted thereon a car 43 for carrying large rock and the like from the hopper to the end of the dredge which are then thrown overboard, or dumped in a scow or the like. 85 In the drawings I have illustrated a car for this purpose, but it is to be understood that any suitable conveyer may be used. This car may be operated by cables, not shown, fixed upon a suitable hoist 44, illustrated in Fig. 2 of the drawings. A suitable engine house D is also mounted upon the dredge and has mounted therein the usual furnace and boiler for supplying steam to the winches and hoists 19, 31 and 44, as before 90 described and in the usual and well known manner.

The letter E indicates a well known means for locating the under current which forms no part of the present invention but is shown 100 for the purpose of illustration.

After the scoop has received its desired load and been brought to a point to be dumped on the hopper 41, the same is tilted to one side and dumped upon the said hopper. This hopper consists of a plurality of beams being covered by a plate 45 having ribs 46 formed thereupon which are spaced apart so that when the gravel or stone is dumped upon the plate different sized gravel will be directed toward the grizzly 47 which acts as a sieve whereby the larger rocks will drop into the car 43 and the smaller gravel containing the valuable ingredients or particles will fall through the grizzly into a compartment 48.

A pump 49 is mounted upon the dredge as preferably shown in Fig. 2 of the drawings and has extending therefrom a discharge pipe 50 whereby the gravel and water may be sucked from the pipe 38 and discharged through the pipe 50 into the compartment 48. Extending from the compartment 48 is a flume 51 which is provided with riffles, not shown, to catch the gold and other particles and discharge the gravel and water back into the river. This flume 51 extends beyond the stern of the scow so that the gravel and water may be discharged at some point distant from the stern end of the scow. 130

This hydraulic pump and cleaning mechanism, as before briefly described, is more clearly illustrated and claimed in my Patent Number 974,150.

Reference now being had to the remaining figures shown in the drawings I will more fully describe the particular parts of my invention in detail. In Figs. 4 and 6 I have more clearly illustrated my improved 10 scoop or dipper 15 which is preferably made of sheet metal and in the construction shown, has a body portion which is rigidly secured to the arm 16 and is further supported by a reinforced boss 52. Formed 15 upon one edge of the scoop are a plurality of digging points 53 which are adapted to dig into the gravel or sand, thereby facilitating the gathering of a load. Secured to each side of the scoop are chains 54 which 20 are spaced apart adjacent their upper ends by means of a spreader 55 and are then connected by a link to the cable 20 as before mentioned. Reference being had to Fig. 4 of the drawings it will be particularly noted 25 that the handle 16 is riveted to the lower edge of the scoop 15 and to one side of the center thereof. This is to provide means whereby when dumping the scoop the same may be operated in the direction of the arrow shown in this figure and the contents thereof dumped upon the hopper 41 when the cable 20 has become slackened.

To provide means for supporting the dipper when in a raised position and when it is 30 desired to tilt the same, I provide a member which I will term a dumping hook 56 which consists of an arm 57 pivotally connected as at 58 in brackets 59 bolted upon one leg of the forward supporting member 12. The 35 arm 16 is provided with the grooved collar 60 which is to be engaged by the hook member when the scoop is being tilted. To provide means whereby the hook member 56 may be brought into position, or swung out 40 of the way when the scoop is in operation, a cable 61 is connected at one end to the hook members as at 62 and then extended over a pulley 63 mounted on the supporting member 12 and then down to a hydraulic ram 64, or suitable means for operating the same. Any suitable form of hydraulic ram designated 45 64 may be used for operating the dumping hook, which ram in turn may be operated in any suitable manner as from the hoist 19.

The arm 16 is provided with an off-set portion 65 which is rigidly connected to the main body portion of the arm by means of flanges 66. This is to provide means whereby when the dipper is tilted to one side it will deposit the contents upon the hopper and when lowering the dipper, the same will stay within the center of the opening 14 formed within the scow. The remaining 55 portion of the arm 16 is smooth throughout

so that the same may reciprocate and oscillate through the grooved roller 17. This grooved roller 17 is mounted in a suitably fastened bracket 67 which also has mounted therein a small guide roller 68, which engages and guides the arm 16. The grooved roller 17 is also provided with a recess 69 whereby the cable 22 may operate upon said pulley without interfering in any way whatsoever with the arm 16.

70

75

The pulley 28 upon which is mounted the cable 25 is mounted between the standards 18 as more clearly shown in Fig. 12 of the drawings. This pulley is provided with blocks which are adapted to travel within a track 70 formed in the inner face of the standards 18, whereby the said pulley may be raised or lowered in the positions illustrated in dotted lines in Fig. 1 of the drawings. This pulley or sheave may be fixed 80 by any suitable or well known means between the standards at any predetermined point, the object of which is to permit a better gripping hold upon the scoop when the same is gathering the deposit of very 85 deep or shallow channels. The pulley 28 is in its lowest point when used for gathering the gravel from deep channels and raised to its highest point between the members 18 when gathering the ingredients from shallow 90 streams or channels. The adjustable arm 16 is cylindrical in cross section and comprises a plurality of members which are 95 adapted to be detachably secured together whereby the arm may be formed of any desired length so that the scoop 15 may gather the gravel from the bottom of the bed of deep as well as shallow rivers. These sections or members forming the arm 16 are 100 so connected together that the outer periphery thereof will be smooth so that the arm will not bind but will freely operate upon the grooved roller 17. To provide this connecting means I provide cylindrical members 72, the exterior diameter of which is 105 approximately the same as the interior diameter of each of the sections. Each of the sections 71 is riveted to the members 72 at 73. A bracket member 74 is secured to the end of each of these members 72 and has 110 a slot formed therein, in and to which the rods 75 are received and bolted, whereby in assembling the different sections, the members are held rigidly in place by the rods 75.

115

The pulley 21 is pivotally mounted within 120 the end of the supporting members 13 to prevent any binding of the cable 20 during the raising or lowering motion of the dipper, or when the same is being tilted, as before described. This pulley 21 is journaled 125 within a casing 76 which has extending from each end thereof pinions 77 mounted within bearings formed upon transverse members 78 which connect the outer extremity of the supporting beams 13. This 130

pulley 21 is pivotally mounted in a diagonal position as preferably shown in Fig. 9 of the drawings so that the cable 20 may be in alinement with the hoist 19.

5 It is apparent from the foregoing description taken in connection with the accompanying drawings that the above dipper dredge may be used in conjunction with my hydraulic dredge of Patent Number 974,150, 10 whereby any deposits or gold bearing gravel which is found in the bed of the river may be easily and readily removed in sufficient quantity consistent with the cost of operating and constructing a dredge of this character.

15 It is further obvious from the foregoing that I have constructed a device which will perform all the necessary requirements, with little friction in operating the various parts, 20 easy to construct and cheap in the cost of manufacture.

It is to be further understood that other minor details of construction may be resorted to that come within the scope of the 25 appended claims without departing from the spirit of the present invention.

Having described my invention, what I claim as new and desire to secure by Letters Patent, is:—

30 1. In combination with a scoop, an arm rigidly connected therewith, a frame structure, a pair of grooved mounting rollers carried by said frame structure to have the arm extended therethrough to be capable of raising and lowering and axial turning movement, means to cause the arm to have extensible and contractible movement between said rollers, a hook to support the arm in the raised position, and means by which the arm 35 is given axial turning movement when in the raised and supporting position to cause the scoop to be dumped.

2. In combination with a scoop, an arm with which the scoop is rigidly connected to 45 be carried, a supporting frame, a bracket mounted on said frame to have the arm passed therethrough, grooved rollers carried by said bracket to have the arm extended through the grooves thereof to permit raising and lowering and axial turning movement of the arm, means to extend and contract the arm through the mounting between said rollers, means to raise the arm to elevate the scoop to a dumping position, 50 means to engage said arm to support the scoop in the raised relation and to permit axial turning movement of the arm, and means to turn the arm to accomplish a dumping of the scoop.

55 3. In combination with a supporting structure, an arm carried by said supporting structure to be capable of raising and lower-

ing movement and also axial turning movement, a scoop rigidly mounted on one end of said arm off center with respect to the turning axis thereof, means for lowering said arm to fill the scoop and raising the same to bring the scoop to the dumping position, and means to support the arm in the raised relation while at the same time permitting the 65 axial turning of the arm to permit dumping of the scoop.

4. In a device of the character described, the combination with a supporting member, an adjustable arm mounted therein, an offset portion formed on said arm, a scoop mounted on said arm and to one side of the center thereof, means for raising and lowering said arm, and means for tilting said scoop.

5. In a device of the character described, the combination with a supporting structure, a supporting member mounted upon said structure, an adjustable arm mounted upon said supporting member to be capable 85 of axial turning movement, a scoop mounted on said arm in an offset relation, means whereby said arm may be raised and lowered and means to turn said arm axially in the direction of the offset of the scoop to 90 accomplish a dumping of the same.

6. In a device of the character described, the combination with supporting structure, grooved rollers mounted upon said structure, an adjustable arm mounted within 95 said rollers, said arm being cylindrical in cross-section and the mounting thereof arranged to permit axial turning movement, the lower end of said arm being off-set, a scoop secured to said arm adjacent said off-set portion, and means arranged to accomplish axial turning of said arm to operate with the offset portion thereof to swing said scoop to its laterally tilted dumping relation.

7. In a device of the character described, a supporting member, grooved rollers mounted on said supporting member, an arm mounted between said grooved rollers to be capable of extensible and contractile 110 movement and to also permit axial turning thereof, a scoop connected with one end of said arm at a point laterally of the center of said scoop to offset the same with respect to the axis of the arm, means connected with 115 said arm to operate the same in its longitudinal path of movement, and means to turn said arm axially in the direction of the offset to accomplish a tilting of the scoop to its dumping position.

WILLIAM F. HUNTER.
